SHOE STRETCHING LAST

Joel Koskela, New York, N. Y.

Application June 15, 1940, Serial No. 340,650

11 Claims. (Cl. 12—128.3)

This invention relates to new and useful improvements in a shoe stretching last.

More specifically, the invention proposes the construction of a shoe stretching last constructed to be separable throughout its entire length in a manner to permit the entire interior surface of a shoe to be stretched.

Still further the invention proposes a novel means for securely locking together the rear ends of the last blocks forming the said device for permitting the front ends thereof to be separated any desired distance to permit only the toe of the shoe to be stretched.

Still further it is proposed to provide the device with a heel piece adapted to be engaged against the heel portion of a shoe to permit the length thereof to be slightly stretched and to further hold the front portion of the shoe stretching last in position within the toe portion of the shoe.

Still further the invention proposes a novel means for permitting the normal contour of the shoe stretching last to be increased in a novel manner for permitting the last to be adjusted in size to meet the requirements of differently sized shoes.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is an elevational view of a shoe stretching last constructed in accordance with this invention and showing its position as applied to a shoe.

Fig. 2 is a vertical sectional view on the line 2—2 of Fig. 1.

Fig. 3 is a vertical sectional view on the line 3—3 of Fig. 2.

Fig. 4 is a horizontal sectional view on the line 4—4 of Fig. 3.

Fig. 5 is a plan view of the shoe stretching last in its stretched position.

Fig. 6 is a sectional view on the line 6—6 of Fig. 1.

Fig. 7 is a view similar to Fig. 6 illustrating the open position of the lock member.

Fig. 8 is still another view similar to Fig. 6 illustrating the turned position of the lock member for causing the cam surfaces to be used for spreading the rear end of the last blocks.

Fig. 9 is a sectional view on the line 9—9 of Fig. 1.

Fig. 10 is a view similar to Fig. 1 but illustrating a modification of the invention.

Fig. 11 is a plan view of a portion of Fig. 10.

The shoe stretching last, according to this invention, is adapted to be used in combination with a shoe 10 of any desired construction and includes a pair of complementary adjacent last blocks 11. These last blocks have a wedge hollow 12 disposed between their adjacent faces and intermediate of the ends thereof. A transverse stud 13 is located between the rear end of the wedge hollow 12 and the rear end of the last blocks proper and extends into openings 14 formed in the rear end of the blocks 11. This stud 13 is slidably extended into the openings 14 and the openings 14 are of a size and shape to permit the front end of the blocks 11 to be separated, while the rear ends thereof remain in contact with each other.

A longitudinally extending screw 15 is threadedly engaged through an opening 16 formed in the stud 13. This screw 15 extends coaxially from the rear end of the blocks 11 and is disposed between the adjacent faces thereof. A wedge 17 is rotatively mounted upon the front end of the screw 15 and engages in the wedge hollow 12. The screw 15 has a reduced end 15a which rotatively extends into the wedge 17. The wedge 17 is formed with a hollowed out central area 17a and a pin 18 is engaged through the reduced end 15a of the screw and engages the back face of the hollowed out area 17a for holding the wedge 17 in position upon the reduced end 15a of the screw. The construction is such that when the screw 15 is rotated its threaded engagement with the stud 13 will cause the front end thereof to move forward. This movement will also cause the wedge 17 to move forward and its engagement with the faces of the wedge hollow 12 will cause the front end of the last blocks 11 to be separated, as shown in Fig. 5.

A bridging portion 19 is formed integral with each of the blocks 11 through which the screw 15 freely engages. This bridging portion has forwardly inclined front walls 20 engaging a forwardly disposed concaved surface on the rear of the wedge 17 so that the wedge 17 holds the blocks 11 together when the wedge 17 is in its extreme rearward position. This bridge portion 19 also assists in rotatively supporting the front end of the screw 15.

A bracket 21 is mounted upon the rear end of each of the last blocks 11 and each is semi-circular in shape and adapted to cooperate with each other for forming a complete circle. Each of

the brackets 21 has a cam surface 21^a and a latch element 21^b. The rear end of the last blocks 11 are attached to the sides of the brackets 21 by means of pins 11^a.

5 A tube 22 is turnably and freely mounted upon the screw 15. The front end of the tube 22 freely carries a member 23 which is rotatively supported thereon. The member 23 has a central opening through which the tube 22 passes. The tube 22 10 may be freely moved forwards on the screw 15 till its strikes the transverse stud 13. This member on diametrically opposite sides is formed with a cam surface 23^a and a latch element 23^b. The latch elements 23^b of the member 23 are arranged complementary to the latch elements 21^b of the brackets 21. In a turned position of the member 23, as shown in Fig. 6, the latch elements 23^b are adapted to contact the latch elements 21^b of the brackets 21 for locking the rear ends of the last blocks 11 together. The adjacent faces of the latch elements 23^b and the latch elements 21^b are inclined to engage each other and prevent the member 23 from moving axially out of the bracket 21 in the locked position there- 25 of.

Furthermore, a set screw 24 is threadedly engaged through the side of one of the brackets 21 and is adapted to be engaged against the adjacent face of the member 23 for preventing accidental turning thereof. The member 23 is further provided with a pair of outwardly extending prongs 25 which are adapted to be used for turning the member 23 relative to the tube 22 when the screw 24 is turned to a position in which its inner end is disengaged from the member 23.

When the screw 24 is loosened the member 23 is adapted to be turned to cause its cam surfaces 23^a to engage the cam surfaces 21^a of the brackets 21 and spread the rear ends of the blocks 11.

40 A spread position of the brackets 21 is illustrated in Figs. 5 and 8. In a slightly turned position of the member 23 the screw 24 is also adapted to be turned to cause its inner end to engage the adjacent face of the adjacent cam surface 23^a for holding the member 23 in its adjusted positions. There is nothing to hold the blocks 11 together when separated through their entire length, but the separation is only to be accomplished when the last is in position within 45 a shoe and the engagement of the sides thereof with the inner faces of the walls of the shoe will tend to keep the last blocks in their proper aligned position with relation to each other and with relation to the member 23 and the wedge 17.

50 The last blocks are constructed in a manner to permit shells 27 to be engaged on the outer faces thereof for increasing the normal contour of the last blocks to meet the requirements of various sized shoes. The last blocks 11 are adapted to be used with or without the shell member 27 as controlled by the size of the shoe to which the last is applied.

55 The last, according to this invention, is further provided with a means for holding the front end of the last blocks in a fixed position within the toe portion of the shoe and for permitting the length of the shoe to be increased, if desired. This means comprises a heel piece 28 which has a top portion 28^a threadedly engaging threads 22^a 60 formed on the outside of the tube 22. This heel piece 28 is further provided with a downwardly extending portion 28^b which is adapted to be engaged against the inside face of the heel of the shoe 10 as shown in Fig. 1.

70 The tube 22 is provided at its outer end with a

handle 29 permitting the same to be rotated relative to the heel piece 28 for bringing the heel piece into a proper position in which its downwardly depending portion 28^b will engage the heel of the shoe 10 while the front end of the tube 22 abuts the transverse stud 13. Further rotation of the handle 29 will cause the downwardly depending portion 28^b to more rigidly engage the heel, forcing the last blocks forward into the toe of the shoe, causing the length thereof to be 75 stretched. The outer end of the screw 15 is also provided with a handle 30 for permitting the screw 15 to be rotated relative to the stud 13.

The operation of this form of the invention is as follows:

15 For stretching a shoe the screw 15 is rotated into a position in which the wedge member 17 will engage against the rear end of the wedge hollow 12 for permitting the front ends of the last members 11 to contact each other. The member 23 is then rotated into a position in which its latch elements 23^b will engage the latch elements 21^b of the brackets 21 for locking the rear ends of the last blocks together. The last blocks 11 are then slipped into the shoe 10 with or without the shells 27, depending on the size of the shoe. The heel piece 28 is then engaged against the heel portion of the shoe 10 by rotating the tube 22 relative to the heel piece 28 to cause the last blocks to be securely positioned within the toe portion of the shoe. The screw 15 is then turned relative to the stud 13 which will cause the wedge 17 to move forward within the wedge hollow 12 and spread the toe portions of the last blocks 10 for stretching the toe portion of the 35 shoe.

If it is also desired to stretch the shoe across the arch thereof it is merely necessary to rotate the member 23 relative to the brackets 21 to cause the cam surfaces 23^b to cooperate with the cam surfaces 21^b of the brackets 21 for spreading the rear ends of the blocks 11. For holding the member 23 in its new adjusted position it is necessary to rotate the screw 24 until its inner end engages the adjacent face of the member 23 for 45 holding the same against accidental turning. For moving the shoe stretching last from the shoe 10 the above procedure is reversed.

According to the modification of the invention shown in Figs. 10 and 11, the construction of the 50 shoe stretching last is similar to that previously described, except that the last blocks 11' are superimposed one upon the other and have a split between the adjacent faces extended substantially horizontally instead of vertically, as described 55 relative to the previous form of the invention. The operative mechanism of this modified shoe last is similar to that described relative to the previous form of the invention and like reference characters are used for identifying like parts in 60 the several figures.

This form of the invention further distinguishes from the previous form in a slightly different means for permitting the operative normal contour of the last blocks 11' to be increased. This 65 means comprises an arched plate 35 mounted upon the top last block 11'. This arched plate 35 has its front end pivotally supported by means of a pin 36 and its rear end provided with a means for holding the same in various raised positions 70 with relation to the face of the block 11'. This means includes a lever 37 pivotally mounted upon the rear end of the plate 35 intermediate of its ends.

The front end 37^a of the lever is adapted to 75

cooperate with one of a plurality of ridges 38 formed in the top face of the top last block 11 for holding the plate in any desired position for increasing the arch diameter of the blocks. A turnable eye 39 is mounted upon the top last block adjacent the rear end of the ridges 38 and is adapted to cooperate with an opening formed in the rear end 37^b of the pivoted lever 37 for securely holding the plate 35 in a non-operative position. In other respects this form of the invention is similar to the previous form.

It is to be understood that by means of this arrangement, a shoe may be stretched in all directions, at any desired place, such as, at the toe, vamp, arch, etc., of the shoe, by a simple manipulation of the shoe stretching last.

By means of this arrangement, it is possible to separate the toes of the last blocks by first locking the cam elements 21^b, and then rotating the screw 15.

It is also possible by this device, to keep the toes of the last blocks closed, and to spread the rear end of the last. To accomplish this, the cam elements 21^b are first opened and then the last 25 is pushed far into the toe of the shoe by rotating the handle 29 until the heel piece 28 presses against the back of the shoe. Then the screw 15 is rotated in a direction to move the wedge 17 forward. This motion of the wedge 17 will spread 30 the rear end of the last.

The last may also be spread with the toe and back simultaneously, by first sliding back the cam 17, and by loosening the heel piece 28. Then the screw 15 is again rotated in a direction 35 which will advance the cam 17 forward. This motion will separate both the toe and back portion of the shoe last.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a shoe stretching last, a pair of complementary last blocks engageable into the toe of a shoe and having a wedge hollow in their adjacent faces, a transverse stud between and extending into the rear ends of said blocks, a longitudinally extending screw threadedly engaging said stud, a wedge rotatively mounted on said screw and engaging in said wedge hollow, a bracket mounted on the rear of each last block and having cam surfaces and latch elements, a tube freely mounted on said screw, a member freely and rotatively mounted on said tube and having latch elements complementary to said latch elements for holding said brackets together and cam surfaces complementary to said cam surfaces for holding the rear ends of said last blocks spaced, and means for holding said member fixedly with respect to one of said brackets.

2. In a shoe stretching last, a pair of complementary last blocks engageable into the toe of a shoe and having a wedge hollow in their adjacent faces, a transverse stud between and extending 70 into the rear ends of said blocks, a longitudinally extending screw threadedly engaging said stud, a wedge rotatively mounted on said screw and engaging in said wedge hollow, a bracket mounted on the rear of each last block and having cam surfaces and latch elements, a tube free-

ly mounted on said screw, a member freely and rotatively mounted on said tube and having latch elements complementary to said latch elements for holding said brackets together and cam surfaces complementary to said cam surfaces for holding the rear ends of said last blocks spaced, and means for holding said member fixedly with respect to one of said brackets, said wedge being formed with a central hollow, said screw being formed with a reduced end rotatively engaging said wedge, and a pin engaging through the reduced end of said screw and engaging the back wall of said central hollow for holding said wedge in position upon said screw.

3. In a shoe stretching last, a pair of complementary last blocks engageable into the toe of a shoe and having a wedge hollow in their adjacent faces, a transverse stud between and extending into the rear ends of said blocks, a longitudinally extending screw threadedly engaging said stud, a wedge rotatively mounted on said screw and engaging in said wedge hollow, a bracket mounted on the rear of each last block and having cam surfaces and latch elements, a tube freely mounted on said screw, a member freely and rotatively mounted on said tube and having latch elements complementary to said latch elements for holding said brackets together and cam surfaces complementary to said cam surfaces for holding the rear ends of said last blocks spaced, and means for holding said member fixedly with respect to one of said brackets, said means for rotatively mounting said member upon said tube comprising an opening in said member through which said tube passes.

4. In a shoe stretching last, a pair of complementary last blocks engageable into the toe of a shoe and having a wedge hollow in their adjacent faces, a transverse stud between and extending into the rear ends of said blocks, a longitudinally extending screw threadedly engaging said stud, a wedge rotatively mounted on said screw and engaging in said wedge hollow, a bracket mounted on the rear of each last block and having cam surfaces and latch elements, a tube freely mounted on said screw, a member freely and rotatively mounted on said tube and having latch elements complementary to said latch elements for holding said brackets together and cam surfaces complementary to said cam surfaces for holding the rear ends of said last blocks spaced, and means for holding said member fixedly with respect to one of said brackets, said means for holding said member comprising a screw threadedly engaged through one of said brackets and cooperative with the adjacent face of said member.

5. In a shoe stretching last, a pair of complementary last blocks engageable into the toe of a shoe and having a wedge hollow in their adjacent faces, a transverse stud between and extending into the rear ends of said blocks, a longitudinally extending screw threadedly engaging said stud, a wedge rotatively mounted on said screw and engaging in said wedge hollow, a bracket mounted on the rear of each last block and having cam surfaces and latch elements, a tube freely mounted on said screw, a member freely and rotatively mounted on said tube and having latch elements complementary to said latch elements for holding said brackets together and cam surfaces complementary to said cam surfaces for holding the rear ends of said last blocks spaced, and means for holding said member fixedly with respect to one of said brackets,

...said latch elements on said member and said latch elements on said brackets being provided with complementary inclined faces for preventing said member from moving axially out of said brackets.

6. In a shoe stretching last a pair of complementary last blocks engageable into the toe of a shoe and having a wedge hollow in their adjacent faces, a transverse stud between and extending 10 into the rear ends of said blocks, a longitudinally extending screw threadedly engaging said stud, a wedge rotatively mounted on said screw and engaging in said wedge hollow, a bracket mounted on the rear of each last block and having cam 15 surfaces and latch elements, a tube freely mounted on said screw, a member freely and rotatively mounted on said tube and having latch elements complementary to said latch elements for holding said brackets together and cam surfaces 20 complementary to said cam surfaces for holding the rear ends of said last blocks spaced, and means for holding said member fixedly with respect to one of said brackets, and a bracket mounted adjacent the rear end of said wedge hollow and through which said screw extends for 25 assisting said stud in supporting said screw.

7. In a shoe stretching last, a pair of complementary last blocks engageable into the toe of a shoe and having a wedge hollow in their adjacent faces, a transverse stud between and extending into the rear ends of said blocks, a longitudinally extending screw threadedly engaging said stud, a wedge rotatively mounted on said screw and engaging in said wedge hollow, a bracket mounted on the rear of each last block and having cam surfaces and latch elements, a tube freely mounted on said screw, a member freely and rotatively mounted on said tube and having latch elements complementary to said latch elements for holding said brackets together and cam surfaces complementary to said cam surfaces for holding the rear ends of said last blocks spaced, and means for holding said member fixedly with respect to one of said brackets, and a shell comprising separate shell sections, each of said shell sections being engageable upon one of said last blocks for increasing the normal operative contour thereof.

- 50 8. In a shoe stretching last, a pair of complementary last blocks engageable into the toe of a shoe and having a wedge hollow in their adjacent faces, a transverse stud between and extending into the rear ends of said blocks, a longitudinally extending screw threadedly engaging said stud, a
55 wedge rotatively mounted on said screw and engaging in said wedge hollow, a bracket mounted on the rear of each last block and having cam surfaces and latch elements, a tube freely mounted on said screw, a member freely and rotatively
60 mounted on said tube and having latch elements complementary to said latch elements for holding said brackets together and cam surfaces complementary to said cam surfaces for holding the rear ends of said last blocks spaced, and means for
65 holding said member fixedly with respect to one of said brackets, said last blocks being superimposed one on the other.

9. In a shoe stretching last, a pair of complementary last blocks engageable into the toe of a

shoe and having a wedge hollow in their adjacent faces, a transverse stud between and extending into the rear ends of said blocks, a longitudinally extending screw threadedly engaging said stud, a wedge rotatively mounted on said screw and engaging in said wedge hollow, a bracket mounted on the rear of each last block and having cam surfaces and latch elements, a tube freely mounted on said screw, a member freely and rotatively mounted on said tube and having latch elements complementary to said latch elements for holding said brackets together and cam surfaces complementary to said cam surfaces for holding the rear ends of said last blocks spaced, and means for holding said member fixedly with respect to one of said brackets, said last blocks being superimposed one on the other, and means upon the top face of said top last block for increasing the operative diameter of said last blocks.

10. In a shoe stretching last, a pair of complementary last blocks engageable into the toe of a shoe and having a wedge hollow in their adjacent faces, a transverse stud between and extending into the rear ends of said blocks, a longitudinally extending screw threadedly engaging said stud, a wedge rotatively mounted on said screw and engaging in said wedge hollow, a bracket mounted on the rear of each last block and having cam surfaces and latch elements, a tube freely mounted on said screw, a member freely and rotatively mounted on said tube and having latch elements complementary to said latch elements for holding said brackets together and cam surfaces complementary to said cam surfaces for holding the rear ends of said last blocks spaced, and means for holding said member fixedly with respect to one of said brackets, and a heel piece mounted on said tube and engageable with the heel of said shoe for securely holding said last blocks in position within the toe thereof and for stretching the length of the shoe when desired. 40

11. In a shoe stretching last, a pair of complementary last blocks engageable into the toe of a shoe and having a wedge hollow in their adjacent faces, a transverse stud between and extending into the rear ends of said blocks, a longitudinally extending screw threadedly engaging said stud, a wedge rotatively mounted on said screw and engaging in said wedge hollow, a bracket mounted on the rear of each last block and having cam surfaces and latch elements, a tube freely mounted on said screw, a member freely and rotatively mounted on said tube and having latch elements complementary to said latch elements for holding said brackets together and cam surfaces complementary to said cam surfaces for holding the rear ends of said last blocks spaced, and means for holding said member fixedly with respect to one of said brackets, and a heel piece mounted on said tube and engageable with the heel of said shoe for securely holding said last blocks in position within the toe thereof and for stretching the length of the shoe when desired, and means for causing said heel piece to be moved along the length of said tube with relation to said last blocks for permitting the same to be engaged with said heel.

JOEL KOSKELA
